CLAIM

The ornamental design for a lamp, as shown and described.

DESCRIPTION

FIG. 1 is a top, front, and left side perspective view of a light showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken-line disclosure in the views is understood to represent portions of the article in which the claimed design is embodied, but which forms no part of the claimed design.

1 Claim, 3 Drawing Sheets
